DESIGN FOR A THERMOMETER

Herman Neuwirth, Brooklyn, N. Y.

Application December 14, 1936, Serial No. 66,516

Term of patent 14 years

To all whom it may concern:

Be it known that I, Herman Neuwirth, a citizen of the United States and a resident of the Borough of Brooklyn, county of Kings, city and State of New York, have invented a new, original, and ornamental Design for a Thermometer, of which the following is a specification, reference being had to the accompanying drawing, forming part thereof.

In the drawing,

Figure 1 is a plan view of a thermometer showing my new design with the tube and its supports omitted, and

Figure 2 is a front elevation thereof.

I claim:

The ornamental design for a thermometer, as shown and described.

HERMAN NEUWIRTH.
